(57) **CLAIM**

The ornamental design for a rechargeable lotus lamp, as shown and described.

DESCRIPTION

FIG. 1 is a top perspective view of a rechargeable lotus lamp design showing my new design.

FIG. 2 is a bottom perspective view of the rechargeable lotus lamp.

FIG. 3 is a front view of the rechargeable lotus lamp.

FIG. 4 is a rear view of the rechargeable lotus lamp.

FIG. 5 is a left view of the rechargeable lotus lamp.

FIG. 6 is a right view of the rechargeable lotus lamp.

FIG. 7 is a top view of the rechargeable lotus lamp; and, FIG. 8 is a bottom view of the rechargeable lotus lamp.

The broken lines in the drawings are for the purpose of illustrating portions of the rechargeable lotus lamp that form no part of the claimed design.
